(57) **CLAIM**

The ornamental design for a lamp as shown and described.

DESCRIPTION

FIG. 1 is a top perspective view of a lamp showing my design.

FIG. 2 is a bottom perspective view thereof.

FIG. 3 is a front side elevational view thereof. The back side elevational view is a mirror image of the front side elevational view.

FIG. 4 is a left side elevational view thereof. The right side elevational view is a mirror image of the left side elevational view.

FIG. 5 is a top plan view thereof; and,

FIG. 6 is a bottom plan view thereof.

Although usable in other ways, the lamp is intended to be used for providing light.

1 Claim, 6 Drawing Sheets
